JACK

Filed June 4, 1928

William B. Rungan, INVENTOR
BY Marechal and Roe, ATTORNEY

UNITED STATES PATENT OFFICE

WILLIAM B. RUNYAN, OF DAYTON, OHIO, ASSIGNOR TO THE DAYTON MALLEABLE IRON COMPANY, OF DAYTON, OHIO, A CORPORATION OF OHIO

JACK

Application filed June 4, 1928. Serial No. 282,722.

This invention relates to lifting jacks and particularly to jacks of the multiple lift type.

One object of the invention is to provide a lifting jack of the multiple lift type having a plurality of threaded lifting members, the jack being simple and cheap in construction and arranged so that the lifting members may readily be raised or lowered through the remote operation of its operating mechanism.

Another object of the invention is the provision of a lifting jack having a rotatable driving member for operating a lifting member, this rotatable member having provisions for retaining it on the standard and for conveniently operating it directly by hand.

Other objects and advantages of the invention will be apparent from the following description and from the accompanying drawings in which—

Fig. 1 is a vertical sectional view through a jack constructed in accordance with the present invention;

Fig. 2 is a central vertical section on the line 2—2 of Fig. 1;

Fig. 3 is a horizontal section on the line 3—3 of Fig. 1; and

Fig. 4 is an end view of the driving member.

As illustrating a preferred embodiment of the invention a double screw jack particularly adapted for use in connection with vehicles equipped with balloon tires is herein set forth. Referring to the drawings the jack comprises a hollow standard 10 having a base 11. Loosely mounted within the standard is a hollow or sleeve-like outer lifting member 12 provided with a cylindrical bore or passage 13. This member 12 is externally threaded as indicated at 14 and is received within a rotatable collar 15 which is internally threaded as indicated at 16 to engage with the threads 14 of the outer screw member. The collar 15 is rotatably supported by the standard 10, preferably at the upper end thereof, and suitable ball bearings or other antifriction means 17 are preferably interposed between the lower end of the collar 15 and the upper end of the standard 10, to insure relatively easy rotation of the collar with respect to the standard. The standard 10 is provided adjacent its upper end with the

yoke 20, having an opening 21 therein through which the outer screw member 12 readily moves, the yoke being provided with a down turned flange 22 adjacent the opening 21 for cooperating with the upper end of the collar 15 to restrain upward movement thereof and maintain the collar in operative position on the standard. The yoke is also provided with a guide opening or passage 25 within which is mounted the rotatable driving or socket member 26. This socket member carries a bevel pinion 30 upon the inner end thereof, which meshes with a bevel gear 31 carried by the collar 15, the arrangement being such that rotation of the driving or socket member 26 will cause rotation of the collar 15 in one direction or the other.

The socket member 26 is provided with a non-circular opening 32 adapted to receive a correspondingly shaped end of a suitable operating handle 33 so that that rotatable driving or socket member 26 can be rotated remotely or from a convenient distance. The operating handle 33 is adapted to be easily inserted and removed from the socket 32 and it will be understood that customarily when raising a load the operating handle 33 is used. The socket member 26 is retained against inward axial movement within the sleeve 25 by an irregularly shaped wire device or lock ring 34 preferably of spring steel or the like and mounted near the end of the socket member so as to abut against the end of the adjacent portion of the standard. This wire device 34 extends outwardly in lobes beyond the adjacent surface of the sleeve portion of the standard and engages a shallow groove 60 provided near the end of the socket member, at the ends 61 and at the depressed portions 62 of the wire device between adjacent lobes. The ends 61 are cut off sharply as shown and are arranged to meet the shallow groove portion of the socket member at a suitable angle so that these ends have a tendency to dig into the metal of the socket member and prevent relative turning of these parts in either direction. The wire device 34 is sprung on the end of the socket member and when in place it abuts the end of the adjacent portion of the standard and thus serves 100

the dual purpose of restraining the socket member against endwise movement and also forming a convenient and accessible hand-operated device adapted to permit the direct 5 manual movement of the socket member and the consequent movement of the lifting member of the jack without employing the remotely operated handle 33. The lobe portions of the wire device, projecting as they 10 do beyond the adjacent cylindrical standard portion can readily be operated by the thumb and fingers of the hand of the operator to approximately adjust the position of the lifting members so that the jack is ready to engage 15 a load, or so that the lifting members may be lowered into their lower retracted positions.

Adjacent the upper end of the bore 13 the 20 inner wall of the main or outer screw member 12 is provided with internal screw threads as shown at 35, which are adapted to engage the external threads of an inner screw member 36 which is thus received by the outer screw member. Upon relative rotation of the 25 outer and inner screw members the latter will be moved axially either up or down relative to the former. The inner screw member is provided at its upper end with a saddle or cap 37 which is adapted to receive the 30 load, such as the axle of an automobile, this cap being preferably rigidly secured to the member 36 by means of a fastening pin or by any other suitable means.

The construction, as thus far described, is 35 such that upon rotation of the collar 15 relative to the outer screw member 12, the latter is caused to move up or down within the standard. Likewise rotation of the outer screw member 12 relative to the inner screw member 36 will cause the latter to be moved either up or down within the outer screw member. Consequently, should the socket member 26 and the collar 15 be rotated while the cap 37 is in engagement with the load, 40 there will be either a rotation of the collar with respect to the outer screw member to cause axial movement of the latter, or the outer screw member may rotate with the collar to cause axial movement of the inner screw member. However the jack must ordinarily be operated somewhat before the cap is brought into contact with the load, and the present invention contemplates the provision of means for yieldingly resisting rotation 45 of the outer screw member relative to the standard so that axial movement of the outer screw member 12 within the collar may result during the initial operation of the jack.

A slide member 40 is provided having one 50 or more lugs 41, 42 which are guided vertically and are freely slidable in the standard in slots or guides 43 which extend along the inner wall of the standard to points 44 adjacent the cylindrical guide surface 45 near the ball bearing and thus prevent rotation of this

member 40 during operation of the jack. The slide is provided with a cylindrical portion 46 which is freely received in the lower end of the outer screw member 12. A transversely extending hole 47 in the slide member 40 receives a pair of steel balls 48 between which is a spring 49 which presses the balls outwardly. The size of the hole 47 is just slightly larger than the diameter of the balls 48 so that the latter may be moved in a radial direction within the hole. The balls are adapted to normally project somewhat beyond the outer cylindrical surface 46 of the slide member 40 and into a shallow groove 50 extending circumferentially around the inner cylindrical bore near the lower end of the outer screw member 12. At one point along the shallow groove 50 is a socket or pocket 52, preferably only a little less in extent than the diameter of the balls, which may be caused by drilling a hole 53 through the wall of the outer screw member as shown in Fig. 2, which pocket 52 acts as a non-positive or yielding lock for resisting rotational movement of the balls within the groove 50. When one of the balls is thus engaged within this pocket the pressure of the spring is effective to hold the ball within the enlargement to thus interpose a yielding resistance to rotation of the outer screw member with respect to the standard. As the ball is only partially received in the pocket 52, as shown in Fig. 2, the pressure of the spring may be overcome and the ball may be forced out of the enlargement to permit rotation of the outer screw member in the standard. The balls, the shallow groove 50, and the pocket 52 thus serve to hold the member 40 within the lower end of the bore of the outer screw, and also yieldingly resist rotation of the outer screw. When the collar 15 is rotated the outer screw tends to rotate with it; but the resistance of the member 40, due to the yielding locking of the balls in the pocket 52, tends to overcome this rotative effect and the outer screw is therefore held against rotation, so that it will travel axially, until this yielding locking effect is overcome,—as will occur when the upward travel of the member 40 brings the lugs to the upper ends of the grooves 43. By increasing or decreasing the strength of the spring 49, the relative depth of engagement of the balls in the pocket 52, the abruptness of the walls of the pocket 52, etc., the degree of yielding resistance may be varied.

The assembly of the various parts of the jack is accomplished in a very simple manner merely by inserting the spring and then the balls in the hole 47 of the slide member 40 and then pressing the slide member in the end of the outer screw member until the balls spring out and engage the shallow groove 50, and it will also be apparent that the parts

are very simple in their construction and are easily and cheaply made.

The operation of the jack will now be apparent. Upon rotation of the socket 26, the collar 15 is rotated, and if the load is not engaged by the cap 37, the outer screw member 12 will be moved axially without rotation, the yielding restraint of one of the balls 48 in the enlargement 52 at the lower end 10 of the outer screw member being effective to yieldingly restrain rotation of the outer screw member at this time. During the elevation of the outer screw member, before engagement with the load, the inner screw 15 36 moves with the outer screw member and remains in its lowermost or normal position within the outer screw. When the load is engaged by the cap 37 rotation of the inner screw member is prevented. Upon continuing the rotation of the collar 15 the outer screw member 12 may be either rotated or moved axially dependent upon the strength 20 of the spring 49 and the two screw members are thus raised until the pin 55 which is provided in one of the thread grooves of the outer screw member engages the lower face 25 of the collar 15. Further axial movement of the outer screw member without rotation is thus prevented, and the outer screw member 30 is then rotated with the collar 15 to screw the inner screw member 36 out of the outer screw member. It will be apparent that the inner screw member 36 will be moved axially by rotation of the outer screw member 12 as 35 the former is prevented from turning by the engagement of the cap 37 with the load. A pin 56 provided in a thread groove of the inner screw member near its bottom end is provided to engage the lower end of the internal threads 35 to prevent the inner screw 40 member from being screwed entirely out of the outer screw member.

To effect the lowering of the load, and the withdrawal of the screw members into the standard, the collar 15 is rotated in a reverse direction. The outer screw member will thus be moved axially in a downward direction until the lower end of the outer screw member is adjacent the base of the 50 standard, at which time a pin 58 engages the top of the collar 15 to prevent any further axial movement. During this lowering of the outer screw member its rotation is yieldingly prevented in the standard by the effective operation of the balls 50 one of which remains seated in the pocket 52. The yielding engagement of the balls with the outer screw member is overcome after the outer screw member has been lowered and when 55 the pin 58 engages the top of the collar 15 so that the outer screw member is caused to rotate with the collar to withdraw the inner screw member. After the load is disengaged the inner screw member may readily be rotated so that it is screwed into the

outer screw member to its extreme lower position in case the disengagement of the load occurs before the inner screw member is entirely withdrawn into the jack.

While the form of apparatus herein described constitutes a preferred embodiment of the invention it is to be understood that the invention is not limited to this precise form of apparatus, and that changes may be made therein without departing from the scope of the invention which is defined in the appended claims.

What is claimed is:

1. A lifting jack comprising a hollow standard, an externally threaded outer screw member mounted in the standard, an inner screw member threaded in the outer screw member, means for elevating the screw members comprising an internally threaded rotatable collar engaging the threads of the outer screw member, and means yieldingly carried by the outer screw member for relative rotational movement with respect thereto and comprising a member slidably guided in the standard for causing axial movement of the outer screw member on rotation of the collar.

2. A lifting jack comprising a hollow standard, an externally threaded outer screw member mounted in the standard, an inner screw member threaded in the outer screw member, means for elevating the screw members comprising an internally threaded rotatable collar engaging the threads of the outer screw member, means carried by the outer screw for axial movement therewith and fixed against rotation in the standard, and a spring-pressed device provided in said last named means for yieldingly engaging the lower end of the outer screw member for causing it to be moved axially by rotational movements of the collar.

3. A lifting jack comprising a hollow standard, an externally threaded outer screw member mounted in the standard, an inner screw member threaded in the outer screw member, means for elevating the screw members comprising an internally threaded rotatable collar engaging the threads of the outer screw member, and means for causing axial movement of the outer screw member comprising a slide telescopically received in the lower end of the outer screw member, a guide in the standard for said slide, a lug on said slide received in said guide, and a spring-pressed ball held in said slide, said outer screw member having a shallow groove receiving said ball to cause the slide to be moved axially with the outer screw member, said groove having an enlarged portion partially receiving the ball to yieldingly restrain relative rotation of the outer screw member and the slide.

4. A lifting jack comprising a hollow standard, an externally threaded outer screw

member mounted in the standard, an inner screw member threaded in the outer screw member, means for elevating the screw members comprising an internally threaded rotatable collar engaging the threads of the outer screw member, and means yieldingly carried by the lower end of the outer screw member and movable axially therewith and comprising a member positively restrained against rotational movements by the standard for causing axial movement of the outer screw member on rotation of the collar.

5. A lifting jack comprising a hollow standard, an externally threaded outer screw member mounted in the standard, an inner screw member threaded in the outer screw member, means for elevating the screw members comprising an internally threaded rotatable collar engaging the threads of the outer screw member, means movable axially at all times with the outer screw member and fixed against rotation in the standard, and a spring pressed device provided in said last named means for yieldingly engaging the lower end of the outer screw member for causing it to be moved axially by rotational movements of the collar.

6. A lifting jack comprising a standard, a rotatable interiorly threaded driving member mounted in the standard, an exteriorly threaded screw sleeve meshing within the driving member, the sleeve being also interiorly threaded, a second screw meshing with the internal threads of the sleeve and cooperating means comprising a guide-way on the standard and a friction clutch carried by the screw sleeve for normally resisting rotary movement of the sleeve, but yielding to permit the sleeve to turn with the driving means when at the limits of its vertical movement, said clutch frictionally engaging the screw sleeve and having a projection thereon extending into said guide-way and making therein a non-rotatable longitudinally slideable connection with the standard.

7. In an extension device, a frame, an extensible member arranged in said frame, an operating member carried in said frame in position to threadingly engage a portion of said extensible member, means for rotating said operating member relatively in said frame to move said extensible member axially therein and means having a splined connection with the frame and frictional engagement with the extensible member and carried by said extensible member and cooperating between said frame and said extensible member to normally prevent relative rotation between said frame and said extensible member which might otherwise be caused by the relative rotation of the operating member and the friction at the threaded connection between it and the extensible member.

8. In an extension device, a frame, a threaded extensible member arranged in said frame, an operating member carried in said frame in position to threadingly engage said extensible member, means for rotating said operating member relatively in said frame to move said extensible member, and friction means arranged between said frame and said extensible member for preventing relative rotation therebetween, said means comprising a member having keyed connection with the frame and frictional engagement with the extensible member.

9. In an extension device, a frame, an extensible member arranged in said frame for projection and retraction with respect to the frame, an operating member carried in said frame and having threaded engagement with said extensible member, means for actuating said operating member to move said extensible member axially in the frame, and friction means arranged between said frame and said extensible member for preventing relative rotation therebetween, said means including a member keyed to the frame and having frictional engagement with the extensible member, said frictional engagement being sufficiently great to overcome the rotational urge imparted to said extensible member by the operating member through the threaded connection between the operating member and the extensible member when the operating member is actuated.

10. In an extension device, a frame, an extensible member arranged in said frame for projection and retraction with respect to the frame, an operating member carried in said frame and having threaded engagement with said extensible member, means for actuating said operating member to move said extensible member axially in the frame, and friction means arranged between said frame and said extensible member for preventing relative rotation therebetween, said means including a member having positive keyed connection with the frame and frictional engagement with the extensible member, said friction member being carried at the lower end of the extensible member.

11. In an extension device, a supporting frame, an extensible member arranged in said frame, an operating member rotatably mounted in said frame and having operating threaded engagement with said extensible member and means frictionally engaging and carried by said extensible member and having splined engagement with said frame to retard the relative rotation of the extensible member with respect to the frame.

12. In an extension device, a frame member, a lifting member arranged in said frame, an operating member rotatably mounted in said frame and having threaded connection with said extensible member whereby the ex-

tensible member may be axially moved with respect to said frame upon rotation of said operating member, means for rotating said operating member, and a device extending

5 between said extensible and frame members, said device having frictional engagement with one and splined engagement with the other whereby to normally prevent relative rotation of said extensible member with respect to the frame.

10 13. In an automobile jack, a frame providing a standard having a vertical channel therein, a lifting member arranged in said frame and telescoping in said channel, an operating member comprising an internally threaded nut supported in the frame at the upper end of the channel, said lifting member threading through said operating member and a second lifting member having a load carrying head at its upper end threading into said first lifting member, cooperating stops limiting the projection of the first member through the operating nut and the second member through the first mentioned member

15 20 25 and a member carried by the first mentioned member and having frictional engagement therewith and having a portion providing splined connection with the frame.

30 14. An automobile jack, a frame providing a standard having a vertical channel therein, a lifting member arranged in said frame and telescoping in said channel, an operating member comprising an internally threaded nut supported in the frame at the upper end of the channel, said lifting member threading through said operating member and a second lifting member having a load carrying head at its upper end threading into said first lifting member, cooperating stops limiting the projection of the first member through the operating nut and the second member through the first mentioned member, means for rotating said operating member and a friction device carried by the first lifting member and engaging the frame to normally prevent rotation of said extensible member with respect to the frame but yielding to permit rotation of said extensible member, said frictional device having means forming a splined engagement with the frame and frictional engagement with the lifting member.

35 40 45 50 55 60 65 15. In an extension device, a frame, an extensible lifting member arranged in the frame in position to be retracted and projected axially therefrom, an operating member rotatably mounted in the frame and having threaded connection with said extensible member for imparting axial movements thereto, said extensible member being formed to provide a shoulder adjacent its lower end, and a spring pressed clutch member operatively associated with said shoulder and having keyed connection with the frame whereby

said extensible member is normally held against rotation.

In testimony whereof I hereto affix my signature.
